UNITED STATES PATENT OFFICE.

ERNEST M. PISTOR, OF DUNDEE, ILLINOIS, ASSIGNOR OF ONE-HALF TO AUGUST T. PISTOR, OF OAK PARK, ILLINOIS.

GAUZE-PACKING DEVICE.

Application filed March 17, 1922. Serial No. 544,517.

To all whom it may concern:

Be it known that I, ERNEST M. PISTOR, a citizen of the United States, residing at Dundee, Kane County, Illinois, have invented certain new and useful Improvements 5 in Gauze-Packing Devices, of which the following is a specification.

These improvements relate to means for packing gauze into a wound or body cavity 10 as part of a surgical or therapeutical operation.

The medical and surgical professions are well acquainted with a form of gauze packer which consists of a relatively long tubular 15 member having a long slender rod or feeder within it, the front end portion of the rod being provided with a pair of diverging prongs, its other end having a head or enlargement which may be grasped by the 20 hand. In the operation the old form of device mentioned the tubular member is grasped by one hand, the end of a strip of gauze in roll form is impaled upon the prongs, and the pronged end of the feeder 25 with the gauze secured thereto is then inserted in the rear end of the tubular member and pushed in as far as it will go. The feeder having the pronged end is then retracted somewhat and pushed forward again, 30 and by repeating this back-and-forth motion the prongs successively engage the material farther to the rear within the tube forcing the material forward and out of the front end. Before this gauze-packing operation is 35 begun, however, the instrument is first inserted in the body of the patient so that its front end is at the place where the gauze is to be applied as a packing. The tubular member must then be held with one hand 40 while the gauze is being inserted, and subsequently so long as the feeding operation is continued, through the movement of the other hand. Various objections to the older form of device are encountered in practice, 45 among which may be mentioned the difficulty of holding the instrument steadily with two hands while performing the packing operation, the disadvantage of having both hands engaged during that operation, the presence 50 of a roll of gauze lying loosely somewhere in the vicinity of the specific place of operation, the twisting of the gauze or the necessity for careful watching of it to prevent twisting while being fed through the device, 55 importantly, the fact that the gauze is con-

taminated by its rolling and tumbling about and by its being handled during the feeding operation as well as at the time of insertion into the instrument, and importantly also, unless the operator is exceedingly careful in 60 the back-and-forth motion of the feeder the gauze packs and jams in the hollow interior of the tubular member and will not go through, in most cases necessitating a withdrawal of the gauze already packed and the 65 beginning of the operations anew. This jamming of the gauze within the tubular member occurs chiefly when the feeder is retracted too far and too much of the gauze is thereby attempted to be forced through 70 at a single forward impulse. It is quite difficult in practice to exercise the desired care in this feeding operation.

The principal objects of the present improvements are to provide a device which 75 avoids the disadvantages of the older form of gauze-packing device mentioned, to the end, among other benefits, that sanitary gauze may be easily and expeditiously applied to the wound or cavity as desired, with 80 a notable reduction of discomfort to the patient and with improved facility of operation and satisfaction on the part of the operator, as well as a greater measure of safety to the 85 patient.

In the accompanying drawings, which form a part of this specification, Figure 1 shows a resilient rod adapted to be inserted in the device to provide a rounded end advantageous when applying the instrument 90 in the body cavity; Fig. 2 is a side view of the instrument complete; Fig. 3 is a medial vertical longitudinal section through the device of Fig. 2; Fig. 4 is a fragment of a rear end part showing a bayonet slot; Fig. 5 is 95 a rear end view of the device.

My improved instrument includes what may suitably be termed a pistol-grip handle 10 of such dimensions and shape as to be comfortably held by a single hand of the operator. A tube 11 is rigidly secured upon the handle, as by sweating it fast within the tubular upper end 12 of the handle. A reciprocating tubular member 13 fits for easy sliding movement within the hollow interior of the tube 11, and a relatively long tubular member 14 fits so loosely within the tube 13 that the tube 13 may slide upon the inner end portion of the tube 14.

The tube 14 has secured to it a head 15 116

having an annular projection 16 which fits snugly within the tube 11. A bayonet slot 17 in the tube 11 and a pin 18 on the part 16 are adapted to lock the tube 14 strongly 5 to the tube 11 when the device is in use while permitting removal of the tube 14 for sterilizing purposes or for substituting one of greater or lesser length as a particular occasion may suggest.

10 A downwardly extending lug 20 upon the sliding tube 13 fits loosely in a slot 21 in the tube 11, part of the handle or frame being also cut away as indicated in Fig. 3, to permit longitudinal movement of the projection 20 and of the tube 13.

15 Upon the handle is pivoted at 23 a lever having a finger piece 24 and an arm 25 pivotally connected at 26 to the link 27, which link is also pivoted to the projection

20 20 at 28. It is thus apparent that a pull upon the finger piece 24 will move the tube 13 forward. A leaf spring 30 secured to the handle and pressing against the stud 31 retracts the parts to their initial positions 25 when the pressure is withdrawn from the finger piece 24.

A circular gauze housing or receptacle 33 is provided closely adjacent to the rear end of the tube 13. Its side wall has a slot 34 30 through which issues a strip of gauze 35 from the roll within the receptacle 33. One side wall 32 of the receptacle 33 is readily removable, being held by a bayonet slot connection as shown by Fig. 5, whereby the 35 gauze may be inserted. As noted from Fig. 2 the gauze 35 leads to an enlarged and outwardly-flared opening at 38, produced by an expansion of the metal of the tube there, and the lower half of the tube 13 is cut away at 40 40 whereby there is provided ample room for the feeding of the gauze into the hollow interior of the sliding tube 13.

The rod or feeder 42 is a piece of slender wire bifurcated and thereby provided with 45 two diverging prongs 43 at its front end, its rear end having the button or head 44 with a projection 45 extending therefrom and into the end of the tube 13, there being a pin 46 on the part 45 held in the bayonet 50 slot 47 in the tube 13. The rod 48 of Fig. 1 has a similar head 49 and a pin 50 whereby this rod 48 may be similarly positioned and held by the tube 13.

The operation of the device is as follows: 55 The feeder 42 being removed from the tubes 13 and 14, a roll of gauze 35 is freed from its paper wrappings and may be placed in the receptacle 33 without its being touched by the operator's hand. While in that position the prongs 43 of the feeder may be made to catch into the free end of the gauze and the gauze may be drawn so as to pass through the slot at 34, whereupon the covering lid 32 may be placed upon the receptacle 60 65 33. The prongs 43 and the gauze held by

them are inserted at 38 into the tube 13 and thence into the tube 14, the feeder being pushed forward its full length and being then made secure to the tube 13 by means of the pin 46 and bayonet slot 47. Thereupon, by merely holding the device in one hand the finger-piece 24 may be pulled upon by a finger or fingers of the hand which holds the device, the sleeve or sliding tube 13 being moved forward thereby and carrying the feeder 42 forward relative to the tube 14. Upon releasing the pressure upon the finger piece the spring 30 retracts the parts, including the prongs 43, for another engagement with the gauze, and thereupon another pull projects the gauze forward the amount of the stroke. This operation is continued until the packing operation is substantially complete, the gauze automatically feeding into the tubes 13 and 14 and without contact with any extraneous object. By cutting the gauze between the receptacle 33 and the tube 13 and continuing the operation all of the free material is soon packed into the body cavity and thereupon the instrument may be removed.

It is to be understood that for inserting the device into the body cavity the rod of Fig. 1 is first inserted in the instrument whereby the head 52 projects somewhat beyond the end of the tube 14 and forms a rounded end for this part of the device. The instrument of Fig. 1 is then removed, without removing the tube 14, and the gauze-feeding device is then put into operation as 100 hereinabove described.

The device being entirely of metal and being susceptible of being readily taken apart and reduced to smaller units is easily to be maintained in sterile condition. The pistol-grip and the arrangement of the tube 14 substantially pistol-barrel fashion upon the grip provide for an unusually advantageous control of the device in use. The stroke is a predetermined one, and is never more than that which will result in satisfactory operation, whereby jamming of the gauze in the tube is avoided. The construction also provides the various other advantages hereinabove pointed out.

I contemplate as being within the scope of these improvements various changes, modifications and departures from what is specifically herein illustrated and described, as indicated in the appended claims.

I claim:

1. A gauze-packer of the character described comprising in combination a handle adapted to be gripped substantially in the palm of a hand of the operator, a relatively long gauze tube open at its forward end carried by said handle, said tube having an opening adjacent to the handle for the admission of a strip of gauze thereinto, a gauze feeder extending longitudinally within said

- tube, said feeder having means for engaging a strip of gauze to feed it forward within said tube and out of the forward end thereof with a step-by-step movement, and means for 5 moving the feeder longitudinally with a reciprocating motion, said means including a lever operable by a part of the hand gripping said handle when the device is normally in use.
- 10 2. A gauze-packer of the character described comprising in combination a handle adapted to be gripped substantially in the palm of a hand of the operator, a relatively long gauze tube open at its forward end carried by said handle, said tube having an opening adjacent to the handle for the admission of a strip of gauze thereinto, a gauze feeder extending longitudinally within said tube, said feeder having means for engaging a 15 strip of gauze to feed it forward within said tube and out of the forward end thereof with a step-by-step movement, a lever operable by a finger of the hand normally gripping said handle for moving the feeder longitudinally 20 in one direction, and spring means for moving the feeder in the opposite direction, to provide a reciprocating motion for the feeder.
3. A gauze-packer of the character described comprising in combination a handle adapted to be gripped substantially in the palm of a hand of the operator, a relatively long gauze tube open at its forward end carried by said handle, said tube having an 25 opening adjacent to the handle for the admission of a strip of gauze thereinto, a gauze feeder extending longitudinally within said tube, said feeder having means for engaging a strip of gauze to feed it forward within 30 said tube and out of the forward end thereof with a step-by-step movement, means carried by the device for supporting a supply of gauze for delivery to the interior of said tube, a lever operable by a finger of the hand normally gripping said handle for moving the feeder longitudinally in one direction, and 35 spring means for moving the feeder in the opposite direction, to provide a reciprocating motion for the feeder.
4. A gauze-packer of the character described comprising in combination a pistol-grip handle, a tubular member carried by said handle in substantially pistol-barrel relation thereto, a gauze tube open at each end, means for holding the gauze tube in readily removable relation to said tubular member at the forward end of said tubular member, a tubular gauze-feeder-holder mounted for reciprocation within said tubular member, said feeder-holder being open at its forward 40 end and having an opening for the admission thereto of a strip of gauze, a relatively long and slender gauze-feeder within said tube and within said feeder-holder, means for holding the gauze-feeder in readily removable relation to the feeder-holder, and means for reciprocating said feeder-holder, said means including a lever operable by the hand normally holding said handle.
5. A gauze-packer of the character described comprising in combination a pistol-grip handle, a tubular member carried by said handle in substantially pistol-barrel relation thereto, a gauze tube open at each end, means for holding the gauze tube in readily removable relation to said tubular member at the forward end of said tubular member, a tubular gauze-feeder-holder mounted for reciprocation within said tubular member, said feeder-holder being open at its forward 50 end and having an opening for the admission thereto of a strip of gauze, a relatively long and slender gauze-feeder within said tube and within said feeder-holder, means for holding the gauze-feeder in readily removable relation to the feeder-holder, and means for reciprocating said feeder-holder, said means including a lever operable by the hand normally holding said handle.

E. M. PISTOR.
